HEATING APPARATUS

Bernard Goerg, Bronxville, N. Y., assignor to American Radiator & Standard Sanitary Corporation, New York, N. Y., a corporation of Delaware

Application January 15, 1942, Serial No. 426,806

3 Claims. (Cl. 122—225)

My invention relates to heating apparatus and more particularly to hot water and steam boilers of the type commonly employed in comfort heating of buildings; and it has for an object to provide a boiler of improved construction and arrangement of parts.

A further object is to provide a boiler of the type referred to which is specially suited for use with tap water heating systems employing a hot water heating coil of the submerged type.

A still further object is to provide a new and improved back section for use in boilers of the type composed of a plurality of vertical sections arranged in side-by-side relation.

The invention consists in the novel construction and combination of parts; to be more fully described hereinafter, and the novelty of which will be particularly pointed out and distinctly claimed.

In the accompanying drawings, to be taken as a part of this specification, I have fully and clearly illustrated a preferred embodiment of my invention, in which drawings—

Fig. 1 is a longitudinal vertical section taken on the line 1—1 of Fig. 2 and illustrating my invention as embodied in an oil-fired boiler of the type composed of vertical sections arranged in side-by-side relation;

Fig. 2 is a horizontal plan section taken on the line 2—2 of Fig. 1; and

Fig. 3 is a transverse vertical section through the upper part of the rear boiler section, the view being taken on the line 3—3 of Fig. 1.

Referring now in detail to the construction illustrated, the reference character 10 indicates a boiler which is shown as comprising a front section 11, a rear section 12, and two intermediate sections 13 and 13a. It will be appreciated that in practice the number of intermediate sections used will be varied to suit the output requirements of the particular heating system of which the boiler is to be a part.

Each of the boiler sections is formed of cast-iron and in one piece and is formed with hollow walls providing interior spaces adapted to contain the boiler water when the boiler is used as a part of a hot water heating system, and adapted to contain boiler water with steam in the top part thereof when the boiler is used as a part of a steam heating system. In Fig. 1 of the drawings, I have elected to illustrate the boiler as it is used to generate steam. The water level is indicated at 14 and the steam space at 15. 16 indicates the steam supply pipe and 17 the condensate return. The boiler sections are ar-

ranged in vertical side-by-side relation and the water spaces thereof are communicatively connected at the bottom by the usual nipples 18, and the water and steam spaces thereof are communicatively connected at the top by relatively large nipples 19. As shown, the water level is maintained above the bottom of the top nipples 19 so as to provide for the circulation of boiler water between sections and thereby maintaining an approximately uniform temperature of boiler water in all of the sections. As is common in boilers of this type, the several sections are rigidly held in their assembled relation by the usual tie rods 20.

15 The front section 11 comprises two vertically arranged water legs 21 and 22 located, respectively, at opposite sides thereof and forming the two front vertical corners and the forward portions of the two side walls 23 and 24 of the boiler. The vertical legs 21 and 22 are connected at the bottom of the boiler by a horizontal water leg 25, at the top of the boiler by a second horizontal water leg 26, and intermediate of the boiler by a third horizontal water leg 27. The vertical legs 21 and 22 are also connected across the front by a hollow transverse waterway 28. Three vertically spaced openings 29, 30, and 31 are provided through the front wall 32 of the boiler. The top opening 29 serves as a clean-out opening and is closed by a door 33; the intermediate opening 30 functions as an inspection opening and is closed by a door 34; and the bottom opening 31 is a firing opening and is closed by a cast-iron plate 35 suitably bolted to the front face of the section 11. The plate 35 is shown as being provided with an opening 36, through which the discharge tube 37 of a gun type oil burner 38 extends.

20 The intermediate boiler sections 13 and 13a are identical in construction, and each comprises two vertical water legs 40 and 41 located, respectively, at opposite sides of the boiler and forming a portion of the two boiler side walls 23 and 24. The vertical water legs 40 and 41 of each intermediate section are connected at three vertically spaced points; viz., at the bottom by a horizontal water leg 42, at the top by a horizontal water leg 43 and intermediate of the top and bottom by a third water leg 44. The top leg 43 and intermediate leg 44 of each intermediate section are connected at horizontally spaced points by short vertical legs 45 and 46 (see Fig. 2). The vertical legs 40 of sections 13 and 13a are vertically aligned with one another, as shown, and form 25 the intermediate portions of boiler side wall 23,

and the vertical legs 41 of sections 13 and 13a are also vertically aligned with one another and form the intermediate portions of boiler side wall 24.

The back section 12 also comprises a pair of vertical water legs 50 and 51 located, respectively, at opposite sides of the boiler and forming the rear portions of the two side walls 23 and 24 of the boiler. The two vertical legs 50 and 51 are connected at the bottom by a horizontal water leg 52 and at the top by a horizontal water leg 53. The two vertical legs 50 and 51 are connected at their two vertical rear corners by a transverse vertical waterway 54 extending across the rear of the boiler and forming the boiler rear wall 55. The waterway 54 can be considered for purposes of description as the main water space of the back section and the vertical legs 50 and 51 as both the ends and as forward extensions of the main water space. The top leg 53 and bottom leg 52 also have forward extensions and which terminate on the same transverse vertical plane as the legs 50 and 51.

When the sections 11, 12, 13, and 13a are assembled, as shown, the bottom water legs 25, 42, and 52 are horizontally aligned with one another and form the bottom wall 58 of the boiler, and the top water legs 26, 43, and 53 are also horizontally aligned with one another and form the top wall 59 of the boiler. The intermediate water legs 27 and 44 are horizontally aligned with one another and form a division, or baffle wall 60 extending horizontally across the interior of the boiler.

The space within the interior of the boiler and beneath the baffle wall 60 functions as a combustion chamber 61, and the space above this baffle wall 60 functions as the boiler flue space 62, through which the gaseous products of combustion flow from the chamber 61. If desired, a fire-box 63 of suitable refractory material may be positioned in the lower part of the combustion chamber 61. The fire-box 63 is shown as being provided with an opening 64 through which air and fuel is discharged from the burner 38 by the discharge tube 37. If desired, a suitable horizontal crown-sheet baffle 65 may also be provided to assure a more thorough contact of the combustion gases with the interior wall surfaces of the combustion chamber 61.

The rear section 12 is provided with a relatively short vertical leg 67 extending forwardly from the main water space, or waterway 54, and downwardly from the top horizontal water leg 53. The lower end of the water leg 67 is joined to the vertical side leg 50 by a relatively short horizontal leg 68. The short legs 67 and 68 can also be considered as forward extensions of the main water space of section 12 and they terminate forwardly in the same vertical plane as the legs 50, 51, 52, and 53. The short vertical leg 67 is vertically aligned with the vertical legs 45 of sections 13 and 13a, and the short horizontal leg 68 is horizontally aligned with those portions of the legs 44 of sections 13 and 13a, which lie between their respective vertical legs 40 and 45.

The rear section 12 also comprises a tubular-shaped wall 70 which extends longitudinally of the boiler and through the main water space 54 and defines a flue-gas outlet 71 adapted to be connected at its rear or discharge end with the usual chimney or stack (not shown). As shown, the flue-gas outlet 71 is arranged alongside the boiler wall 23 and at one side of the central longitudinal axis of the boiler which is indicated in

Fig. 2 by the dotted line A. As can be seen from an examination of Fig. 2, the tubular wall 70 also forms one of the defining walls for each of the short legs 67 and 68, and the inner defining wall for the upper part of vertical leg 50. The wall 70 also forms a part of the lower wall of the forward or overhanging extension of the upper leg 53.

The short vertical leg 67 and the vertical legs 45 of sections 13 and 13a form a vertical partition or baffle wall 73 through the flue space 62 and which divides the latter into a flue pass 74 extending forwardly along the side wall 24 and a flue pass 75 extending rearwardly along the side wall 23. As the front section 11 above the leg 27 has no vertical leg corresponding to the legs 45, the two flue passes 74 and 75 are joined at the front to form a single U-shaped flue passage connected at its inlet end with the combustion chamber 61 through an up-take passage 77 and terminating at its other or discharge end in the flue-gas outlet 71. The up-take passage 77 is the open space between the lower part of the short vertical leg 67 and the forwardly extending portions of the vertical leg 51 directly opposite thereto. The short vertical legs 46 of sections 13 and 13a divide the flue pass 74 and advantageously provide additional heat absorbing surfaces for the boiler.

The main water space of the rear section 12 is defined by a front transverse vertical wall 80 and a rear transverse wall 81. The upper part 81a of the rear wall 81 is spaced rearwardly from the upper part 80a of the front wall a substantially greater distance than the lower part 81b is spaced from the lower part 80b of the front wall. This construction provides an enlarged water chamber 85 at the upper and rear of the boiler and extending unobstructed from outer vertical side wall 86 of vertical leg 51 and inwardly beyond the central longitudinal axis A of the boiler, and terminating inwardly in the tubular wall 70 defining the flue-gas outlet 71. As can be seen from an examination of Fig. 2, the enlarged water chamber 85 is positioned directly behind the up-take passage 77 and that the upper part 80a of the front defining wall 80 thereof, is engaged by the hot combustion gases as they leave the combustion chamber 61. The vertical fins 87 formed on the upper wall part 80a aid further in the efficient absorption of heat by such part 80a.

From the foregoing, it is apparent that this enlarged unobstructed and efficiently heated water chamber 85 is made possible due to the off-center location of the flue-gas outlet 71, and also due to the arrangement of the up-take passage 77 with respect to the chamber 85, the flue-gas off-take 71, and the U-shaped flue passage through the space 62. Because of this construction, the boiler disclosed is especially adapted for use with systems for heating tap water. As shown, a hot water heating coil 90 is disposed within the water chamber 85 and transversely of the boiler and rear section 12. It is noted that the particular hot water heating coil 90 which I have elected to show, is intended for use with the tankless type of tap water heating system; i. e., a system which does not include a storage tank, the coil 90 having enough heat absorbing surface so that water is heated to the desired temperature as it flows once therethrough to the hot water taps. It will be appreciated, however, that water heating coils adapted for use with storage tanks and that other types of tankless

coils, may also be used without departing from the broader aspects of my invention.

The coil 90 comprises two series of pipe coils 91 and 92 connected at their upper and lower ends, respectively, by manifold fittings 93 and 94 rigidly secured to a cast-metal closure plate 95. Each of the series 91 and 92 is formed of two continuous coils of pipe which are connected together at their inner adjacent ends by a manifold chamber 96 formed in the plate 95. Thus, each of the several coils of pipe is secured at its two ends to the cast-metal plate 95 and are supported thereby. The outer side wall 86 of vertical leg 51 of rear section 12 which also forms the rear part of the boiler side wall 24, is formed with a rectangular opening 97 of sufficient size to permit the heating coil 90 to be inserted and removed from the water chamber 85. The plate 95 is suitably bolted to the wall 86 and closes the opening 97. Water service pipes 98 and 99 connect to the manifold fittings 93 and 94, respectively, and one of these pipes is adapted to be connected to the water main or source of water supply and the other to the hot water taps in the building where the boiler is installed.

What I claim and desire to secure by Letters Patent of the United States is:

1. In a boiler composed of a plurality of vertical sections arranged in side-by-side relation, a back section comprising upright front, rear, and side walls spaced apart to provide a boiler water space including an enlarged unobstructed water chamber at the back and upper part of said boiler and in open communication with the remaining portions of said water space and said enlarged water chamber extending from one side wall inwardly of the boiler to at least the longitudinal center line of the boiler and adapted to receive a hot water heating coil; said one side wall having an opening through which the hot water heating coil can be inserted and removed; and walls defining a flue-gas outlet extending longitudinally of the boiler through said water space and at the side of the longitudinal center line opposite to said one side wall.

2. In a boiler composed of a plurality of hollow cast-metal sections arranged in vertical side-by-side relation, a back section comprising first and second spaced upright outer side walls, and spaced front and rear upright transverse walls extending between and joined along their upright marginal portions to said outer side walls to provide an upright waterway arranged across the rear of said boiler; and walls defining a flue-gas outlet passage extending longitudinally of the boiler and through the upper part of said waterway alongside said first outer side wall; said vertical waterway including a water chamber extending unobstructed from said second side wall to said flue-gas outlet passage and being large enough to receive a hot water heating coil; and said second outer side wall having an opening therein through which such coil may be inserted and removed.
3. In a boiler composed of a plurality of hollow cast-metal sections arranged in vertical side-by-side relation, a back section comprising first and second spaced upright outer side walls, and spaced front and rear upright transverse walls extending between and joined along their upright marginal portions to said outer side walls to provide an upright waterway arranged across the rear of said boiler; and walls defining a flue-gas outlet passage extending longitudinally of the boiler and through the upper part of said waterway alongside said first outer side wall; said front and rear transverse walls being spaced apart a greater distance at the upper part of said waterway than at the lower part thereof to provide an enlarged water chamber therebetween and extending unobstructed from said second side wall to said flue-gas outlet passage and being large enough to receive a hot water heating coil; and said second outer side wall having an opening therein through which such coil may be inserted and removed.

BERNARD GOERG.
